(57) **CLAIM**

I claim the ornamental design for a packaged smore, as shown and described.

DESCRIPTION

FIG. 1 is a perspective view of a packaged smore of the claimed design;

FIG. 2 is a front side view of the packaged smore of FIG. 1;
FIG. 3 is a back side view of the packaged smore of FIG. 1;
FIG. 4 is a left side view of the packaged smore of FIG. 1;
FIG. 5 is a right side view of the packaged smore of FIG. 1;
FIG. 6 is a top side view of the packaged smore of FIG. 1; and,
FIG. 7 is a bottom side view of the packaged smore of FIG. 1.
The broken lines shown represent unclaimed subject matter
and form no part of the claimed design.
